LAST JACKS

Stanley Ernest Frampton, Leicester, England, assignor to United Shoe Machinery Corporation, Flemington, N.J., a corporation of New Jersey

Filed Feb. 19, 1959, Ser. No. 794,421

Claims priority, application Great Britain Mar. 4, 1958

7 Claims. (Cl. 12—126)

This invention relates to a jack for a last, of the type commonly employed for presenting a shoe on the last to a shoe machine, and, more particularly, is concerned with improvements in such a jack for facilitating the mounting of a last upon, and its removal from, the jack semiautomatically.

Shoe machines commonly are provided with a jack upon which a last with a shoe thereon is presented to the machine for the performance of an operation upon the shoe. Typically, the jack comprises a jack pin which is received in a socket in the last provided by the usual thimble which is set into the heel part of the last; and the jack pin projects from a last supporting surface on the jack which is engaged by the top surface of the heel part to support the last against such forces as are directed toward the last bottom during the shoemaking operation.

In the manufacture of lasts of the type disclosed in United States Letters Patent No. 2,806,233, granted September 17, 1957, upon an application of A. R. Hubbard et al., greater care than has been exercised before has been given to locating the thimble longitudinally of the last and perpendicular to the top of the heel part. Moreover, with a view to realizing the advantages of the accuracy of such lasts, especially when their use in an automatic machine is contemplated, attention has also been given to providing as close a fit as possible between the jack pin of the machine and the thimble of the last. It has always required considerable care on the part of an operator in assembling a last upon a jack pin to insure that the complete mounting of the last upon the pin is not prevented by a jamming action between the thimble and the jack pin and, with diminished clearance between the thimble and jack pin, the mounting of the last upon the pin and its removal therefrom has become more difficult.

In view of the foregoing, it is a general object of the invention to facilitate the assembly upon and ejection from a jack of a last which is presented to the jack by an operator or by work handling apparatus.

To this end and in accordance with one feature of the invention, the illustrated jack comprises, with a jack pin adapted to be received in the thimble of a last on the jack, a platform for supporting the last by engagement with the top of its heel part, the pin and platform being movable relatively to each other in one direction axially of the pin to cause it to be inserted into the thimble and in the opposite direction to cause the pin to be withdrawn from the thimble, together with means for holding the last against the platform. Upon placing the last upon a jack of this construction, with the thimble over the jack pin and the top surface of the heel part seated upon the platform, a coaxial relationship of the jack pin and thimble is obtained. Moreover, this relationship is maintained throughout the insertion of the jack pin into and its ejection from the thimble by the above-mentioned means for holding the last against the platform

2

whereby any tendency for the thimble and jack pin to become jammed against each other is obviated.

When the jack pin and platform are at one extreme of their relative movement, they have a relation, i.e., 5 last-receiving relation, such that a short terminal portion of the pin projects beyond the platform to facilitate the presentation of the last to the jack with the thimble in register with the jack pin. At this stage of the assembly of the last upon the jack, the above-mentioned means for holding the last against the platform, which is illustrated herein as a detent carried by the platform, is arranged to engage the last at a point opposite to the terminal portion of the pin whereby the detent and pin cooperate to hold the last against the platform. If desired, the terminal 10 portion of the pin may be tapered, as herein illustrated, further to facilitate the registering of the thimble with the pin, as well as the insertion of the last between the jack pin and the detent.

The relative movement between the jack pin and platform may be effected by moving either one relatively to the other. However, as herein illustrated, the platform is mounted to slide upon a post carrying the jack pin 15 axially of the jack pin toward the base thereof to cause the pin to be fully inserted into the thimble, and in the opposite direction to cause the last to be ejected from the pin.

Although the illustrated detent is disclosed herein as 20 cooperating with a positioning plate fixed upon the heel part of the last and as having a notch adapted to receive the detent, it is apparent that the disclosed apparatus 25 may be modified, within the purview of the invention, to accommodate a last lacking a positioning plate, but having a notch like that in the illustrated plate.

The above and other objects and features of the invention 30 will next be disclosed in detail in the following specification, with reference to an illustrative embodiment of the invention shown in the drawing, and will be set forth in the appended claims.

The drawing illustrates applicant's jack 10, in 35 sectional side elevation, having mounted thereon a last L of the type disclosed in the above-mentioned Hubbard et al. patent. The last has a positioning plate P fixed upon the top of its heel part, the plate having formed in the rear end thereof a V-shaped notch N. The last is also provided with a socket afforded by the usual thimble T which 45 passes through the positioning plate and is set into the heel part of the last perpendicular to the top thereof.

The jack comprises a post 12 from the top of which there projects upwardly a jack pin 14, the upper terminal 50 portion 16 of which is tapered and has a frusto-conical form.

The jack pin 14 projects through a clearance hole in a platform 18 having integral therewith a slide 20 which is slidably mounted in a bore in the post 12 so as to 55 permit relative movement between the jack pin and platform axially of the jack pin.

Upon a collar 22 which is fixed to the slide 20 there is mounted a yielding detent 24, the upper end of which is shaped so as to fit within the notch N in the positioning plate P.

With the platform 18 and jack pin in their last receiving relation, as shown in the drawing, the tapered portion 60 16 only of the jack pin projects beyond the work engaging surface of the platform. In mounting a last upon the jack, the thimble T is brought into approximate register with the jack pin and, upon lowering the last to bring the upper surface of the positioning plate completely into engagement with the last supporting surface of the platform, the detent 24 is caused to become biased 65 against the positioning plate within the notch N whereupon the last is gripped between the detent and the jack 70

pin and is held against the platform in complete alignment with the jack pin.

With relative movement between the platform and post toward each other, which may be effected, within the scope of the invention, by movement of either the post or the platform with respect to the other, the jack pin 14 is inserted into the thimble T. Since the detent is carried by the platform, its grip upon the last is constant and maintained at the same point throughout the relative movement of the platform and jack pin. Because of the right-angular relation between the thimble and the upper surface of the positioning plate, on the one hand, and between the jack pin 14 and the platform 18 on the other hand, a coaxial relationship between the jack pin 14 and thimble T is obtained and also is maintained throughout the insertion of the jack pin into the thimble because the last is always held against the platform 18 by the detent 24. Hence, there is avoided any tendency for a jamming action to occur between the jack pin and the thimble which would impede the assembling of the last upon the jack. With a reversal of the above-mentioned relative movement between the jack pin 14 and the platform 18 the latter, in being separated from the jack post, causes the ejection of the last from the jack pin, at the end of which action only the tapered terminal portion 16 of the pin remains within the thimble.

It will now be evident that the use of the tapered portion 16 of the jack pin as a leader or pilot for starting the entry of the jack pin into the thimble facilitates not only the presentation of the last to the jack but also the engagement of the detent 24 within the notch N. Similarly, removal of the last from the jack is facilitated because it is unnecessary to lift the last off the jack axially of the thimble. Moreover, when the positioning plate P has become fully seated upon the platform 18, complete alignment of the thimble and jack pin is effected; and because the last is thus held by the detent 24 the unobstructed insertion of the jack pin into the thimble is insured.

Having described my invention, what I claim as new and desire to protect by Letters Patent of the United States is:

1. A jack for a last comprising a jack pin adapted to be received in the socket of a last on the jack, a platform for supporting the last by engagement with the top of its heel part, said pin and platform being movable relatively to each other axially of said pin in opposite last assembling and ejecting movements, and means carried by said platform for gripping the last at the same point throughout said movements and cooperating with said pin to hold the last against said platform.

2. A jack for a last having a socket for receiving a jack pin and carrying on its heel part a positioning plate having a notch formed therein, said jack comprising a post from which there projects a pin adapted to be received in the socket of a last on the jack, a platform through which said pin protrudes for supporting the last by engagement with the top of said plate, said post and platform being movable relatively to each other in one direction axially of said pin to cause the latter to be inserted into the socket of a last on said platform and in the opposite direction to separate the last and said pin from each other, and means carried by said platform and cooperating with said plate within said notch to prevent displacement of the last away from said platform during the insertion of said pin into the socket.

3. A jack for a last having in its heel part a notch and a socket for receiving a jack pin, said jack comprising a

pin adapted to be received in the socket of a last on the jack, a platform for supporting the last by engagement with the top of its heel part, said pin and platform being movable relatively to each other axially of said pin in one direction to cause the pin to be withdrawn from a last on said platform and in the opposite direction to cause said pin to be inserted into the socket of the last, and means mounted upon said platform for gripping the last within its notch and cooperating with said pin to hold the last against said platform throughout the insertion of said pin into the socket.

4. A jack for a last having in its heel part a notch and a socket for receiving a jack pin, said jack comprising a platform adapted to be engaged by the top of the heel part of a last, a post having a jack pin with respect to which said platform is mounted to slide upon said post axially of said pin from a last receiving position into an operative position to cause said pin to be inserted into the socket of a last upon said platform, and a last gripping member carried by said platform for gripping the last within its notch when said platform is in its last receiving position and cooperating with said pin throughout the insertion thereof into the socket of the last to hold the last against said platform.

5. A jack for a last having a socket adapted to receive a jack pin, said jack comprising a post having a jack pin adapted to be received in the socket of a last on the jack, said pin having a reduced terminal portion, a platform adapted to be engaged by the top of the heel part of a last thereon, said post and platform being relatively movable in opposite directions axially of said pin between a last receiving relation in which the said terminal portion only of said pin projects beyond said platform and an operative relation in which said pin is fully inserted into the socket of the last, and a detent mounted upon said platform so as to engage the last opposite to said terminal portion of said pin when said pin and platform are in last receiving relation, whereby the last is held against said platform by said detent and pin throughout the insertion of said pin into the thimble.

6. A jack for a last having a socket for receiving a jack pin, said jack comprising a post from which there extends a jack pin adapted to be received in the socket of a last on the jack, a platform for supporting the last by engagement with the top of its heel part, said platform being mounted for last assembling movement on said post axially of said pin from a last receiving position in which a terminal portion of said pin projects beyond the platform into the socket, and a last engaging detent above and carried by said platform for cooperating with said pin to hold the last in engagement with the platform when it is in its last receiving position.

7. A jack for a last having a socket for receiving a jack pin and carrying on its heel part a positioning plate the periphery of which is provided with a notch, said jack comprising a post from which there projects a jack pin adapted to be received in the socket of a last on the jack, and a platform for supporting the last by engagement with said plate, said platform being mounted to slide on said post toward and away therefrom axially of said pin, said platform carrying a detent engageable with said plate within its notch and cooperating with said pin to hold the last against said platform.
